GRAPPLER OR GRAB HOOK

David Homer Hayden, Brooklyn, N. Y.

Application November 20, 1933, Serial No. 698,819

12 Claims. (Cl. 294—104)

The invention relates to grapples or grab hooks and seeks to provide a tool of this sort of simple, effective construction, and which is particularly adapted and designed for removing the spreaders 5 from the forms for concrete walls and the like, as the concrete is poured. The invention consists in the features hereinafter set forth, illustrated in the preferred forms in the accompanying drawing, and more particularly defined in the 10 appended claims.

In the drawing:

Fig. 1 is a view in elevation of the preferred embodiment of the improved tool or grapple.

Fig. 2 is a side view thereof, and

Fig. 3 is a view similar to Fig. 1 illustrating a modification.

The tool is provided with a stock or handle 1 of suitable length and which may be conveniently formed of wood. A metal supporting plate 2 is secured to the end of the stock or handle 1 by screws 3 and a pair of cooperating grab hooks or tongs are mounted on the supporting plate. One of the hooks comprises an arm 4 which is fixed at its upper end, as by means of rivets 5, 20 to the lower end of and adjacent the edge of the plate 2, the arm 4 extending in line with the stock or handle 1 and having a pointed or tooth-shaped lower end 6.

The cooperating hook in the form shown in 30 Figs. 1 and 2, comprises an arm 7 having a pointed lower end or tooth 8 and this arm is fulcrumed or connected by a pivot bolt 9 to the end of a swinging arm 10. The latter is pivotally connected at its upper end by means of a stud 11 to the lower end of the supporting plate 2. A heavy coiled spring 12 is connected to the arm 10, and to an offset lug 13 on the lower edge of the plate 2, the parts being so arranged that the spring, as shown, is disposed below the lower 40 end of the handle 1.

The arm or grab hook 7 is provided with a rigid lever arm 14 which is preferably integral therewith. This lever arm extends across the hook or arm 4 and between this arm and a guide bar 45 15. The latter is held in position by the stud 11 and by a stud or bolt 16 which extends through the hook arm 4, the guide bar having offset ends 17 to hold it spaced from the other parts. The lever arm is provided with an inclined cam-shaped lower edge 18 disposed between shoulders 50 19 and 20 and which are arranged to engage the stud or abutment 16 on the fixed hook arm 4. In the form shown, the lever arm 14 is provided on its end with a pointed tooth or hook 21 and adjacent the shoulder 20 with a hook 22. As most

clearly indicated in Fig. 2, the tooth 6 on the lower end of the hook 4 is offset to bring it in line with the tooth 8 of the hook 7.

The closed position of the grab hooks or tongs is shown in full lines in Fig. 1. In this position the shoulder 20 and hook 22 engage the stud or abutment 16. By pressing down on the projecting end of the lever arm 14, this cam edge 18 cooperates with the stud or abutment 16 to move the arm 10 against the pull of the spring 12 and thereby force the movable hook arm 7 to open position and the shoulder 19 of the lever then engages the stud or abutment 16 to hold the hooks in open position as shown in dot and dash lines in Fig. 1. In open position, the part or 10 hook 22 of the cam lever is disposed between and slightly above the teeth 6 and 8 of the grab hooks and when the tool with the grab hooks opened is engaged with any part such as a wooden spreader 23 for concrete forms, the part 22 20 is engaged by the spreader or the like and the shoulder 19 of the lever arm is disengaged from the abutment 16 and the spring 12 then forces the hooks together so that they bite into the spreader and then its removal can be readily 25 effected. It is noted that the arm 14 forms a combined cam lever and latch which cooperates with the abutment 16 for forcing the hooks open against the pressure of the spring 12 and for 30 releasably holding the same in open position.

In the form shown in Fig. 3, the construction and arrangement of the correspondingly numbered parts are the same as in the form shown in Figs. 1 and 2. But in this modification, the swinging or pivoted arm 10' is extended beyond 35 its pivotal connection with the lever arm 14', and the movable tooth or hook 8' is formed thereon instead of on the lever. The lever arm is provided with a curved cam surface 18' and a notch 19' which cooperate with the stud or abutment 40 16, when the lever arm is depressed to force the hooks to open position and releasably hold the same in such position. When the hooks are 45 opened as shown in full lines in this figure, the curved lower edge of the lever arm is in position to be engaged by a wooden spreader or the like to release the latch lever and permit the hooks to bite into the spreader.

Heretofore considerable inconvenience has been encountered in removing the spreaders from 50 the forms for concrete walls and the like, since the spreaders are tightly clamped between the walls of the form and must be removed as the concrete is poured. The present improved grapple forms a convenient tool for this purpose. Its 55

construction is stout and durable and the metal parts can be readily and inexpensively formed from sheet steel stampings. The projecting hooked end of the lever arm can be used to dislodge a spreader that is very tightly held in place and then, by means of the grapple hooks, the spreader can be gripped and lifted from the form.

Changes may be made in the details set forth without departure from the scope of the invention as defined in the appended claims.

I claim as my invention:

1. A grapple comprising a pair of grab hooks or tongs, a spring for forcing the same to closed position, an abutment on one hook and a combined cam and latch lever associated with the other hook and arranged to cooperate with said abutment to force the hooks open against the pressure of said spring and releasably lock the same in open position.
2. A grapple comprising a stock, grab hooks mounted thereon, a spring for forcing the hooks to closed position, and a cam lever connected to one of said hooks and extending beyond the other hook, the latter having an abutment affixed thereto and said lever having a cam edge and shoulder arranged to engage said abutment for forcing the hooks open against the pressure of said spring and releasably holding the hooks in open position.
3. A grapple comprising a stock, fixed and swinging arms thereon, a spring connected to said swinging arm, a lever arm fulcrumed on said swinging arm, an abutment on said fixed arm, said lever arm having a cam edge and shoulder arranged to engage said abutment for shifting said swinging arm against the pressure of said spring and releasably holding the same in shifted position, and cooperating grab hooks formed on said fixed arm and on one of the other arms.
4. A grapple comprising a stock, fixed and pivoted arms mounted thereon, a spring connected to said pivoted arm, a lever arm fulcrumed on said pivoted arm and extending across said fixed arm, the latter having an abutment, and cooperating grab hooks formed on said fixed arm and on one of the other arms, said lever arm having a cam edge and shoulder arranged to engage said abutment to force the hooks open and releasably hold the same in open position.
5. A grapple comprising relatively movable grab hooks spring pressed to closed position, one of said hooks having a lever arm rigid therewith and provided with a cam edge and shoulder arranged to engage the other hook for forcing the hooks apart and for releasably locking the same in open position.
6. A grapple comprising a stock, a pivotally mounted swinging arm and a fixed grab hook on said stock, a spring connected to said swinging arm, an abutment on said fixed hook, and a cooperating grab hook pivoted on said arm and

having a rigid lever arm provided with a cam edge and shoulder arranged to engage said abutment.

7. A grapple comprising a stock, fixed and pivotally mounted grab hooks thereon, a spring connected to said pivoted hook, and a combined cam and latch lever connected to one of said hooks, the other hook having an abutment arranged to be engaged by said lever to force the hooks apart and releasably lock the same in open position.

8. A grapple comprising a stock, fixed and pivotally mounted arms and a guide bar on said stock, a spring connected to said pivoted arm, an abutment on said fixed arm, a lever arm pivotally mounted on said pivoted arm and extending between the guide bar and the fixed arm and provided with a cam edge and shoulder arranged to engage said abutment, and cooperating grab hooks formed on said fixed arm and on one of the other of said arms.

9. A grapple comprising a stock, a pivoted arm, a guide bar and a fixed grab hook on said stock, a spring connected to said pivoted arm, an abutment on said fixed hook, and a cooperating grab hook pivotally mounted on said pivoted arm and having a rigid lever arm extending between the guide bar and fixed hook and provided with a cam edge and shoulder arranged to engage said abutment.

10. A grapple comprising a stock, a pair of grab hooks carried thereby, a spring for forcing the hooks to closed position, an abutment on one hook, and a combined cam and latch lever connected to the other hook and arranged to engage said abutment to force the hooks open against the pressure of said spring and releasably hold the same in open position, said latch lever being arranged to be engaged and tripped by an article between the hooks.

11. A grapple comprising a stock, relatively fixed and swinging grab hooks carried thereby, a spring for forcing said swinging grab hook to closed position, an abutment on one of said hooks, and a combined cam and latch lever connected to the other hook and arranged to engage said abutment for shifting said swinging hook against the pressure of said spring and releasably hold the same in shifted open position.

12. A grapple comprising a stock, relatively fixed and swinging grab hooks carried thereby, a spring for forcing the said swinging grab hook to closed position, a cam lever connected to one of said hooks and extending beyond the other hook, the latter having an abutment and said lever having a cam edge and shoulder arranged to engage the said abutment to shift said swinging hook against the pressure of said spring and releasably hold the same in shifted open position, said lever being arranged to be engaged and tripped by an article between the hooks.

DAVID HOMER HAYDEN.
